UNITED STATES PATENT OFFICE.

JOHN E. GARSIDE, OF PEORIA, ILLINOIS.

DESIGN FOR A GAME-BOARD.

SPECIFICATION forming part of Design No. 22,686, dated August 8, 1893.

Application filed February 11, 1892. Serial No. 421,192. Term of patent 7 years.

To all whom it may concern:

Be it known that I, JOHN E. GARSIDE, a citizen of the United States, residing at Peoria, in the county of Peoria and State of Illinois, 5 have invented a certain new and useful Design for Game-Boards and I do hereby declare the following to be a full, clear, and exact description of the invention, such as will enable others skilled in the art to which it appertains

10 to make and use the same.

This invention relates to designs for game boards of which the following is the specification, reference being had to the accompanying drawing forming a part hereof.

15 The figure of said drawing is a perspective view of the game board showing the peculiar design.

The form of the board is elliptical, and the extreme outer edge is bordered by a continuous 20 chain of circles or scallops A A and inside of this chain of circles nearer the center of the board, is closely ranged a series of semicircular spaces B B having their centers of radiation placed on a line C as shown, the said 25 semi-circles being arranged around one end of the board and along both sides thereof. At the opposite end of the board on the line of the semi-circular spaces B B is a crescent shaped space E. The crescent is placed with 30 its curves opposite to the curves of the spaces

B B. In the immediate center of the board is an elliptical space F and formed at each end of this space are projections G G. The background of the board between the spaces B B and ellipse F is filled in with squares, triangles and rectangular spaces of contrasting colors, and formed as follows: From every point where the semi-circular lines of the spaces B B touch the line C and at the center of radiation of said semi-circles C B, lines K, L, M and 35 N start and come together at the points I and J located within the elliptical space F. Radiating from the said centers I and J are semi-circles drawn at equal distances from each other, and each semi-circular line is connected 40 by the lines O and the space between the semi-circles and the lines M and N are filled in with different colors alternatively arranged as for instance black and white spaces as shown in the drawing. 45

50 I claim—

The design for a game board, as herein described and shown.

In testimony whereof I affix my signature in presence of two witnesses.

JOHN E. GARSIDE.
